STIRRUP BENDING MACHINE

Filed July 11, 1922

5 Sheets-Sheet 5

Patented Oct. 14, 1924.

UNITED STATES PATENT OFFICE.

THEODORE KARDONG, OF MINNEAPOLIS, MINNESOTA.

STIRRUP-BENDING MACHINE.

Application filed July 11, 1922. Serial No. 574,275.

To all whom it may concern:

Be it known that I, THEODORE KARDONG, a citizen of the United States, residing at Minneapolis, in the county of Hennepin and State of Minnesota, have invented a new and useful Stirrup-Bending Machine, of which the following is a specification.

This invention relates to machines for bending metal rods, bars and the like, and the subject-matter of this application is a continuation in part of my application filed July 21, 1920, Serial No. 397,855, for a stirrup bending machine.

The embodiment shown in the drawings for illustrative purposes, is especially designed for bending stirrups used for supporting beam ends in concrete and other building constructions, but it will be understood that the machine is capable of general use in bending metal bars or rods for various purposes.

One of the objects of my invention is to produce a machine of this character that is capable of bending a plurality of rods or bars simultaneously, bending as many as twenty bars in a single operation.

Another object is to facilitate the formation of a plurality of bends, in different directions, in the same rods or bars, and without reversing the bars.

A further object is to produce a light and powerful power-driven bending machine which may be easily operated and controlled by a single attendant, the machine being equipped with gages to insure accuracy as well as speed of operation.

Other objects will appear in the specification which should be read in connection with the accompanying drawings wherever in:

Figure 1 is a side elevation of my machine showing a plurality of stirrups in position for bending.

Fig. 2 is an end elevation taken from the right hand side of Fig. 1, some of the parts being omitted.

Fig. 3 is a top plan view.

Fig. 4 is a plan view showing enough of the machine to illustrate the first bending operation on a stirrup blank.

Fig. 5 is a section of a detail.

Fig. 6 is a sectional view taken on the line 6-6 of Fig. 1, showing the stirrups connected by clips.

Fig. 7 is a vertical longitudinal sectional view taken on line 7-7 of Fig. 3.

Fig. 8 is an end elevation partly in section taken from the left hand side of Fig. 3.

Fig. 9 is a top plan, certain parts being omitted, and showing the last bending operation on a stirrup blank.

Fig. 10 is a sectional detail taken on line 10-10 of Fig. 9.

Fig. 11 is a sectional detail taken on the line 11-11 of Fig. 9.

Fig. 12 is a sectional view taken on the line 12-12 of Fig. 9.

Fig. 13 is a sectional view taken on line 13-13 of Fig. 7.

Fig. 14 is a modification of the construction shown in Fig. 5, with the parts slightly separated to make clear the oiling system.

Fig. 15 is a detail side view to illustrate the mounting of the channel bar and iron reinforcement.

Fig. 16 is a detail plan view showing the bending lugs and the action of the roller in bending the material.

Fig. 17 is a plan view of the hub and showing the curved channel which catches the scales and dirt dropped from the material being bent.

Fig. 18 is a detail side view partly in section, showing the beveled face of the top and the headed bolt which travels in the curved channel.

Fig. 19 is a side view of the headed bolt.

Referring in detail to the drawings, which show the preferred form of my invention, I have shown a main frame comprising four upright posts or columns 1 preferably made of steel angles, upper and lower longitudinal beams 2 and 3, respectively, and upper and lower transverse beams 4 and 5.

Upright columns 6 are suitably secured to the beams 2 and 3 for strengthening purposes. Suitable braces 7 are secured to the upper and lower ends of the columns 1 on the sides and ends of the frame to prevent racking of the frame. The end beams 5 are secured to the lower ends of the columns 1 so that one leg of the angle extends beneath the lower ends thereof, as is clearly shown in Fig. 7. A transverse channel beam 8, preferably having an iron plate 9 closely fitted in its open side and secured to the web of the channel by bolts 10, has its ends engaging the lower edges of the beams 2 and is secured to a top plate 11 as by bolts 10^a passing through the table top. (Figs. 7 and 5.) This beam has an important function to perform as will be later explained.

70

75

90

105

110

The angle iron frame members 2 and 4 at the top of the machine are arranged with one wing at the bottom and directed inwardly and, to form a complete table, planks 5 or wooden members 11^a are employed, the same being cut to fit and to rest upon the upper surface of the horizontal wing of the said angle iron members, the upper face of the planks lying flush with the upper edges 10 of the vertical wings of the irons 2 and 4 and extending from one side of the machine to the other and under the top plate 11, as clearly shown in Figure 7 of the drawings.

The top 11 is preferably of crucible steel 15 and is suitably secured to the side and end beams 2 and 4 by rivets or bolts, and has a thickened and raised portion 12 intermediate the sides and ends. (Figs. 7 and 9.) Two vertical spaced, bending lugs 13 are integral 20 with the raised portion 12 and top 11, and have fillets or webs 12^a, integral with the lugs and raised portions, for the purpose of bracing or strengthening the lugs. Each of the lugs 13 is substantially a right triangular prism, (Figs. 3 and 16), the adjacent opposed faces of which are straight and parallel. The front edges 14 of the bending lugs are rounded so as not to present a sharp corner to the material being bent.

A boss or centralized drop 15 integral 25 with the lower side of the top plate at the raised portion 12 and extending vertically below the center of the space between the lugs 13, is suitably bored to provide a journal bearing for the upper reduced end 16 of a vertical shaft 16^a, mounted in a step bearing 17 at its lower end, the bearing being secured to a transverse channel beam 18. (Figs. 5, 7 and 14.) The shaft 16^a is 30 provided with a key 16^b below the reduced end 16 where fitting into the bore of the hub 19 of a bending head or bracket 20, which hub is suitably bored and provided with a groove for the reception of the key 16^b and rotates on the drop 15, the outer diameter of which is substantially the same as that of the vertical shaft 16^a (Figs. 5 and 7).

The bracket or head 20 is made in one 35 piece and comprises the hub 19, radial arm 21, and a vertical arm 21^a having an upper horizontal arm 22 overhanging the radial arm 21. The bracket 20 extends upwardly through an arcuate slot 23 in the top boards 11^a of the table immediately in front of the bending lugs 13. A square headed vertical pin 24 which passes through the overhanging arm 22 and the radial arm 21 of the bracket or head 20, carries a bending roller 25 having a lower reduced end 26. (Fig. 7.) The arcuate edge of plate 11, bordering the slot 23 and adjacent the roller 25, is preferably beveled at 27 (Figs. 7 and 18), to cause rust and scale dropping from the metal 40 being bent to fall freely below the roller.

The upper plane face of the radial arm 21 has an arcuate channel-shaped groove 28 open at each end, (Fig. 17), which accommodates the T-head of a stud bolt 29, screwed in a lug 29^a projecting from the beveled portion 27 of the plate 11. As the rust and scale drops from the beveled face 27, it is caught by the radial arm 21 and works into the groove 28, and as the radial arm moves back and forth, the head of this bolt 55 will sweep the scale or dirt collected in the groove out at each end and thus protect the bearing of the shaft 16^a from wear. (Figs. 5, 7, 16 and 18.)

A screw plug 30, having a slot for a screw driver, is threaded in a threaded oil hole 31 through the table top 11 for the purpose of oiling the upper bearing of shaft 16^a (see Figs. 5, 7 and 14). The plug may be removed and the hole filled with oil, which 60 finds its way throughout the bearing surface of the journal and hub, inside and outside the centralized drop 15. Fig. 14 shows a modified form of bearing, the parts being 65 slightly separated to disclose the path 70 of the oil.

It will be noted that the oil entering 75 at the opening 31 travels along the path between the parts 16 and 12, until it reaches its highest level. As this is the principal bearing of the machine, it is important that 80 it should be kept well lubricated.

The driving mechanism for the bending arm preferably comprises a horizontal drive 85 shaft 32 mounted in bearings 33, suitably secured to the end columns of the frame, 90 said shaft being arranged to drive the vertical shaft 16^a through a train of reduction gearing. Shaft 32 projects beyond one 95 side of the frame and carries a friction pulley 34 keyed thereto, and normally idle pulleys 35 and 36, connected to any power 100 shaft and driven in opposite directions, 105 cooperate with the pulley 34 to drive the shaft 32 in either direction. The inner 110 surface of the periphery of each idle pulley 115 is adapted to frictionally engage the adjacent conoidal periphery of the friction pulley 34, thus acting as a friction clutch. (Fig. 8.)

The preferred system of reduction gearing 120 comprises a worm 38 keyed to shaft 32, meshing with a worm wheel 39, keyed to a vertical shaft 40, having end bearings 41, and also having a small spur gear 42 125 keyed thereto and meshing with a large spur gear 43 keyed to shaft 16^a. The lower journal bearing 41 is secured to a transverse channel beam 18^a, and the upper bearing 41 is secured to a similar channel beam 18^a. (Figs. 1, 7 and 8.) Thus, because of 130 the great reduction in speed, the power exerted by the bending means is correspondingly increased.

Each of the pulleys 35 and 36 carries a

hub 44, having an annular groove 45 to receive a yoke 46 of a pulley shifting mechanism. The yokes 46 are each secured to an arm 47, adjustably carried on a reciprocating bar 48, which is slidably mounted in guides 49 secured to the end columns of the frame. A rack 50 is adjustably secured to bar 49, and is adapted to mesh with a segmental gear 51 fast to a longitudinal, oscillatable shaft 52 mounted in convenient bearings on the frame. (Fig. 8.) Two bell cranks 53 and 54 integral with a collar 55 are secured to the shaft 52. Links 56 and 57 connect the bell cranks 53 and 54 with treadle levers 58 and 59, respectively, which are pivotally mounted to the frame, as at 60. A slotted treadle lever guide 60^a is secured to one of the columns of the frame. By pressing on the appropriate lever, either one of the idle pulleys 35 or 36 is shifted into clutching engagement with pulley 34 to rotate the bending arm 20 in the desired direction. (Figs. 2 and 3.)

In order to maintain the pulleys 35 and 36 in normally idle position, I have provided an arm 61 secured to the shifter bar 48, and having a head 62 provided with outstanding lugs 62^a in horizontal alignment with threaded bolts 63 which are threaded into suitable brackets 64 on the main frame. Compression springs 65 have terminal engagement with the lugs 62^a and the bolts 63, each spring being arranged between adjustable nuts 66 on the bolts and the head 62, and acting in opposite directions, so that the compression of the springs will normally hold the head 62 controlling the shifter bar in a central or neutral position. The compression of the springs may be adjusted from time to time as they tend to become weaker, by simply adjusting the nuts 66 on the bolts 63. After one of the treadle levers has been depressed to operate the machine, and is released, one of the springs will automatically shift the clutching pulley to neutral position and at the same time return the treadle to its raised position.

It is sometimes important to bring the bending head to a standstill soon after either of the treadles has been released, especially when it is desired to make accurate bends. On account of the momentum of the rotating parts, the bending head might be rotated beyond the desired point. To overcome this difficulty, a brake drum 67 is keyed to the shaft 32, and has an annular groove on its periphery to accommodate a brake band or strap 68, one of the ends of which is pivotally connected to a weighted lever 69. The lever is pivotally mounted on an axle bolt 70 passing through the two legs 71 and 72 of a U-shaped upright, the leg 72 being longer than the leg 71 and secured at

its upper end to the top beam 18^a, the lower end of the uprights being fastened to the lower channel beam 18^a. An arm 73 is integral with lever 69, and receives a threaded rod 74, which is pivotally connected to the other end of the brake band. A weight 75 is adjustable on the lever rod 69 to impart more or less friction as desired. The force of gravity on the right end of the lever (Fig. 1) is communicated to both ends of the brake band. In case the brake should fail, or when an emergency arises, the operator may simply depress the reversing treadle and thus use the clutch as a very effective brake. (Figs. 1 and 8.)

To enable the attendant to determine the exact angle of any bend, a pointer 76 is threaded in the bending head 20, and cooperates with an arcuate calibrated scale 77 mounted on the top plate at one side of the arcuate slot 23, and fastened by rivets or bolts. The operator, by observing the position of the pointer, can determine when to release either of the treadles and may follow the angularity of the bends being made. (Figs. 3 and 4.)

Secured to the bed plate 11 at the rear end is a pair of parallel graduated scale bars 78 and 79 arranged on opposite sides of a center line passing between the bending lugs 13. (Fig. 9.) Each bar has a longitudinal slot 80 to receive an adjustable stop member 81 secured in position by thumb nuts 82 on bolts 83. The ends of the bars remote from the bed plate are joined together by a link or bridge piece 84, which is adapted to hold them in parallel relation. A stock rest or supporting bar 85 is bolted across the two bars 78 and 79 and is adjustable thereon by the bolts 83. The table top 11 is graduated at 79^a (see Fig. 9) to cooperate with the graduations on the scale or gage bars 78 and 79. On the opposite end of the bed of the machine a single centrally arranged graduated longitudinal slotted bar 86, carrying an adjustable stop 87, is removably secured on the top between angle brackets 86^a, and said bar is held under the arc scale 77.

To hold a plurality of bars or rods together for simultaneous bending, I prefer to use one or more clips or clamping members 88, each preferably comprising a narrow U-shaped clamp slotted as at 89. A ring receiving eye 90 is stamped in one leg of the U, and a ring receiving projection or latching ear 91 is stamped out of the other leg. A ring 92 is secured in the eye 90 and carries a strong elastic band or loop 93. Another ring 94 in the free end of the band or loop is adapted to engage in the latching ear 91 to firmly hold the rods in engagement side by side, during the bending operations. However, the clips may be dispensed with when only a single rod is bent,

- since the operator can easily hold it by hand during the bending. By holding the rods at an angle to the table top, bends in different planes may be made in the same bars.
- 5 I prefer to employ wear plates 95 of proper thickness adapted to fit upon the lugs 13 and snugly embrace the rounded bending edges to prevent undue wear. In practice, it is desirable to employ wear plates 10 of different thicknesses to partially close the gap between the lugs, to provide for bending rods of different diameters, the space being necessarily wide in order to accommodate the largest rods the machine is capable of bending. When rods of small diameter are to be bent, a pair of thick wear plates are used. The plates may be dispensed with when relatively large rods are being bent.
- 20 When it is desired to bend stirrups, I proceed as shown in Fig. 4. The stop 87 on bar gage 86 is set at the desired point, determined by the required length of the legs of the U bends which are bent first. One 25 of the treadles, say 58 for example, is depressed to rotate the beveling head 20 to one side, and a single rod or bundle of rods 96 of the same length, firmly clamped together with one or more clips 88 with their 30 ends even, are inserted between the bending lugs 13 with one end abutting against the stop 87. The treadle 59 is then depressed to cause the bending head to rotate and bend the rods around one of the lugs as 35 a fulcrum (see Fig. 4), the operator, at the same time, holding the free ends of the rods to prevent movement thereof. As soon as the first right angle bend is completed, the bending head is reversed by depressing 40 the proper treadle, the rods removed and again inserted in the manner described above to form the other right angle bend, while the bending head is still rotating and thus the second bend may be made without 45 again reversing the machine. After the U bends are completed, the stops 81 are set at a point on the scale or gage bars 78 and 79 determined by the desired length of the stirrups. The bending operations are 50 repeated to produce the hook ends as seen in Fig. 9. During these bending operations, the legs of the stirrups are supported on the cross beam 85.

One of the important features of the invention is the channel bar 8 with its plate iron reinforcement 9, which is shown in detail in Fig. 15 of the drawing. As Figs. 1 and 2 disclose, these elements extend transversely across the machine and are placed 55 as near as possible to the bending strain, this being adjacent to the hub 19. A great deal of strain comes on the bending lugs, particularly when a plurality of bars or rods are bent at one time. It is necessary to 60 make some provision to distribute this

strain, and the channel bar with its reinforcement accomplishes the desired result.

While I have shown and described a preferred embodiment of my invention, it will be understood that various changes involving omission, alteration, substitution and rearrangement of parts may be made without departing from the scope of my invention which is defined in the appended claims.

What is claimed is:—

1. In a bending machine, a table, a stirrup bending abutment on said table, said abutment comprising a prism having one edge rounded, bracing means for the abutment connected to the table, a power operated bending roller cooperating with said abutment, the roller being movable in front of the rounded edge of the abutment and alongside the outer side thereof to bend a rod or bar about the same, and means to control the 80 operation of the bending roller at will.

2. In a bending machine, a metal plate, a pair of spaced lugs rising from the plate, each lug being substantially in the shape of a right triangular prism, the opposing faces of the lugs being parallel and the front edges being rounded, each lug having a bracing web integral with the rear face thereof, and means cooperating with the rounded edges 90 of said lugs to bend rods or bars thereabout.

3. In a bending machine, a metal plate, a pair of spaced lugs integral with the plate, each lug being substantially in the shape of a right triangular prism, the opposing faces of the lugs being parallel and the front edges being rounded, each lug having a bracing web integral with the plate and with the rear face of the lug, and means cooperating with the rounded edges of said lugs to 100 bend rods thereabout.

4. In a bending machine, a plate, a substantially prism-shaped bending lug on said plate having one rounded edge, a removable wear plate telescopically mounted upon and engaging at least two edges of said prism-shaped lug, and movable bending means adapted to bend stock about the rounded edge of said lug and wear plate.

5. In a bending machine, a bending head, a pair of spaced bending lugs adjacent said head, each of said lugs being substantially triangular in cross section and having a rounded edge, each lug having a slidably removable wear plate partially surrounding it and fitting against its rounded edge.

6. In a bending machine, a metal plate, a pair of spaced, substantially prism-shaped bending lugs integral with the plate, hardened wear plates slidable on said lugs and adapted to partially fill the space therebetween to accommodate rods of different diameters, oscillatable bending means adapted to bend rods about one edge of either of said lugs, and power connections and control mechanism for said bending means.

7. In a bending machine, a plate, a pair of spaced vertical prism-shaped bending lugs on the plate having opposed parallel faces adjacent the space therebetween, one edge of each lug being rounded, wear plates telescopically engaging each of said lugs for partially filling the space therebetween, and movable bending means adapted to bend rods, inserted in the space between the lugs, about the rounded edge of either lug at the will of the operator. 70
8. In a bending machine, a table, a pair of vertical spaced rigid bending lugs, hardened wear plates adapted to telescope on said lugs to partially close the gap between the lugs and to prevent undue wear, and a power actuated oscillatable bending head coacting with either of said lugs to bend stock about one or the other at the will of the operator. 75
9. In a bending machine, a table, a pair of vertical spaced bending lugs on the table, said lugs being of the shape of a triangular prism and rounded at one edge, hardened wear plates adapted to telescope on said lugs to partially close the gap between the lugs and to prevent undue wear of said rounded edges, said plates engaging about opposite ends of said lugs, and an oscillatable bending head coacting with either of said lugs depending upon the direction of movement of said head. 80
10. In a bending machine, a frame, a top plate on said frame, a pair of spaced vertical rigid bending lugs on said plate, a vertical oscillatable bending head adjacent said lugs, means for applying power to said head, and means for controlling the direction of movement of said head at will, whereby to bend stock about either of said lugs. 85
11. In a bending machine, a frame, a top plate thereon, having an arcuate slot, a pair of spaced rigid bending lugs on said top plate, a bending head rotatable about an axis intermediate of the lugs, a roller carried by said head, said head passing through said arcuate slot, and driving connections for rotating said head, whereby to bend rods or bars about either of said lugs at the will of the operator. 90
12. In a bending machine, a table, a pair of spaced bending lugs integral with the table top adapted to accommodate rods therebetween, a bending head pivotally mounted for oscillation in front of said lugs and adapted to bend stock in either direction about the same, power connections for actuating said head, and means to control the application of power to said head at the will of the operator. 95
13. In a bending machine, a main frame, a top plate secured to said frame and having an arcuate slot, a rigid bending lug on said plate, a shaft below the plate, a rotatable bending head adjacent said bending lug passing through said arcuate slot and mount- 100
- ed on said shaft below the plate, a scale on the top plate at one side of said slot, a pointer carried by the bending head to travel over the scale, and power actuated means for driving said shaft. 105
14. In a bending machine, a plate having an arcuate slot, lugs mounted on said plate in spaced relation adjacent the center of curvature of said slot, a bending head co-operating with said lugs and passing through said slot, a vertically disposed roller carried by said head and having a reduced lower end, and power actuating connections to said head for moving the roller about said lugs in reversed directions. 110
15. In a bending machine, a frame, a metal top secured to said frame and having an arcuate opening therein, a bending lug integral with the top, a vertical shaft beneath the top and below the bending lug, an upper journal bearing for the shaft cast integral with said top, a bending head rotatable with said shaft and projecting through the arcuate opening in the top and coacting with the bending lug, and means for coupling said shaft to a source of power to move said bending head. 115
16. In a bending machine, a main frame, a top plate on said frame, vertical bending lugs fixed to said plate, an oscillatable bending head movable about said lugs, a vertical power driven shaft, said head being connected to the shaft, and an upper journal bearing beneath the top plate, said upper bearing comprising a boss integral with the plate and having an opening to receive the upper end of the shaft. 120
17. In a bending machine, a table having a metal top plate, a pair of vertical spaced rigid lugs on said plate, a vertical shaft under the space between the lugs and having upper and lower journal bearings, a centralized drop integral with the plate and receiving the upper end of the shaft, said upper end being reduced, the outer diameter of the centralized drop being the same as the diameter of the shaft, a vertical bending head adjacent said lugs and having a hub embracing said drop and secured to the shaft, and an oil opening through said plate in the space between the lugs and communicating with the upper bearing. 125
18. In a bending machine, a frame, a plate on said frame having an oblong thickened portion, a pair of bending lugs on said thickened portion, an arcuate slot in front of the bending lugs, the edge of the slot adjacent the lugs being beveled, a bending head movable in said slot, a shaft, said head having an arm connected to the shaft below said plate, the arm contacting with the underside of the plate adjacent the beveled edge of the slot and having an arcuate channel open at each end, and means secured in said plate and projecting in said channel 130

to prevent scale and dirt from accumulating in the bearing for said shaft.

19. In a bending machine, a frame, a plate on said frame, a pair of bending lugs, an arcuate slot in front of the bending lugs, the edge of the slot adjacent the lugs being beveled, a bending head movable in said slot, a shaft having a bearing on the underside of said plate, said head having an arm connected to the shaft, the arm contacting with the under side of the plate adjacent the beveled edge of the slot and having an arcuate channel open at each end and open at the top, and a T-headed bolt secured in said plate and projecting in said channel to prevent scale and dirt from accumulating in the bearing for said shaft.

20. In a bending machine, a frame, upper longitudinal side beams on said frame, a plate secured to the side beams, bending means on said plate, a transverse beam in contact with and below the side beams and secured to said plate adjacent the bending means and adapted to prevent buckling of the plate under strains due to bending heavy stock.

21. In a bending machine, a frame, upper longitudinal side beams on said frame, a plate secured to the side beams, bending means on said plate, a transverse beam in contact with and below the side beams and secured to said plate adjacent the bending means and adapted to prevent buckling of the plate under strains due to bending heavy stock, said beam being a channeled beam, and a plate fitted in the channel of said beam, and means for securing the plate in position.

22. In a clip for holding bars or rods while being bent, a U-shaped metal strap having a longitudinal slot in each leg, and clamping means passing through said slot and cooperating with said strap to hold a plurality of rods or bars in stacked relation, said clamping means being detachably secured to one side of the strap.

23. In a clip for rods and the like, a U-shaped strap having its legs slotted for a portion of their length, one leg having an eye, and a latching projection provided on the other leg, a ring hinged in the eye, and an elastic band carried by said ring, and a latch ring carried by said band and adapted to removably engage said latching projection.

24. In a bending machine, a plate, lugs on said plate, an oscillatable bending head coacting with either of said lugs, an arcuate graduated scale bar on said plate, and a pointer secured to said head cooperating with the scale, whereby to determine the angularity of the bends being made.

25. In a bending machine, a table, bending means on said table including a pair of rigid spaced lugs, a graduated gage bar

secured to the table and projecting therefrom in alignment with the space between the lugs, and stop means slidably secured on said gage bar forming an abutment for the ends of the stock being bent and adapted to determine the length of the straight portions thereof.

26. A bending machine comprising a table, upstanding lugs on said table and in spaced relation, a bending device rockable about an axis between said lugs adapted to engage the rods and form the desired bends, gage bars secured to the table, and an adjustable stock support carried by the gage bars for supporting the stock being bent.

27. In a bending machine, a table, means on said table for bending rods or bars, a pair of gage bars secured to the table, a cross beam adjustably secured to said bars, and an adjustable stop on each of said gage bars, said gage bars and beam adapted to support the stock being bent and the stops adapted to determine the length of the stock between bends.

28. A bending machine comprising a suitable support, lugs on and rising from the support in spaced relation to each other, a bending device rockable about an axis intermediate of the lugs, a pair of spaced gage bars extending in a direction away from the bending device, and an adjustable stock support carried by the gage bars for supporting the stock during the bending operation.

29. A bending machine comprising a suitable support, lugs on and rising from the support in spaced relation to each other, a bending device rockable about an axis intermediate of the lugs, a pair of spaced gage bars extending in a direction away from the bending device, and an adjustable stock support carried by the gage bars for supporting the stock during the bending operation, the machine also being provided with a gage curved about the axis of movement of the bending device and similarly graduated on opposite sides of the intermediate point of travel of the bending device.

30. In a bending machine, a frame, closely spaced rigid lugs erected thereon, a bending head oscillatable about said lugs adapted to bend rods in either direction about the same, a shaft to carry the bending head, a gearing for driving the shaft, normally idle driving means for driving the gearing, automatic means for maintaining the driving means in idle position, and manual means for connecting the driving means with said shaft, said bending head being operable to bend stock about either of said lugs.

31. A bending machine comprising a suitable frame, an oscillatable bending head, fixed spaced lugs in operative relation to

- the bending head, gearing for driving the head, coupling means for connecting the gearing with a source of power capable of driving the gearing in opposite directions, 5 and means for controlling the coupling means at will.
32. In a bending machine comprising a table, bending lugs on the table, a bending head mounted on a shaft and oscillatable about said lugs, and power actuated means for driving said head, said means comprising a pair of oppositely rotating movable friction pulleys cooperating with a friction member, a shaft carrying said pulleys and 15 friction member, a train of reduction gearing between said shaft and the shaft carrying the bending head, and means for selectively engaging either of said pulleys with the friction member to reverse the movement 20 of said bending head.
33. In a bending machine, a pair of fixed vertical bending lugs, an oscillatable bending head co-acting with either of said lugs to bend rods in either direction about the 25 same, power connections to operate said head, and manually operable means for controlling the power connections whereby to reverse the movement of the head at the will of the operator.
34. In a bending machine, a table, spaced bending lugs on said table, bending means movable about said lugs in either direction for bending rods inserted between the lugs about either of them at will, power-actuated 30 means connected to said bending means, and selective means for controlling the power transmission at the will of the operator.
35. In a bending machine, a table, bending lugs on the table, an oscillatable bending head adjacent the lugs, a shaft on which said head is secured, a reduction gearing for driving said shaft, a pair of power-driven normally idle pulleys rotatable in opposite 35 directions, a friction member between the pulleys for driving said gearing, and a pair of foot pedals operatively connected to said pulleys to move them into frictional engagement with the friction member, whereby to control the movement of the bending head at will. 50
36. In a bending machine, a frame, closely spaced lugs erected thereon in opposed relation, a bending head movable concentrically about a point intermediate of the lugs, a rockable shaft to carry the head, gearing for 55 driving the shaft, normally neutralized driving means for the shaft, and manually controllable means for causing the coupling of the shaft to power means at the will of an operator. 60
37. A bending machine comprising a frame, a rotatable bending head, fixed spaced lugs in operative relation to the bending head, gearing for driving the bending head, coupling means for connecting the gearing 65 with a source of power capable of driving the gearing in opposite directions, means for centralizing and neutralizing the coupling means to cause the bending means to act in opposite relations to the lugs, and means 70 under the control of and appropriate for causing the bending head to be actuated in one or the other of opposite directions.
38. In a bending machine, a pair of fixed bending lugs, oscillatable bending means adjacent said lugs, a shaft to which said bending means is secured, a gearing connected to the shaft, means for connecting and disconnecting the gearing with a source of power whereby to bend rods or bars about either of 75 said lugs at will, and a brake coacting with said power connections for stopping the bending means automatically as soon as the gearing is disconnected, irrespective of the direction of rotation thereof. 80
- In testimony that I claim the foregoing as my own I have hereto affixed my signature. 85

THEODORE KARDONG.
